MOTION-PICTURE CAMERA

Otto Wittel and Frederick G. Knowles, Rochester,
N. Y., assignors to Eastman Kodak Company,
Rochester, N. Y., a corporation of New Jersey

Application August 17, 1950, Serial No. 11,802

Term of patent 14 years

(Cl. D61—1)

To all whom it may concern:

Be it known that we, Otto Wittel and Frederick G. Knowles, citizens of the United States, residing in Rochester, in the county of Monroe and State of New York, have invented a new, original, and ornamental Design for a Motion-Picture Camera, of which the following is a specification, reference being had to the drawings, forming a part thereof, in which:

Fig. 1 is a perspective view taken from the front and showing portions of a side and top of a motion-picture camera showing our new design; and

Fig. 2 is a perspective view taken from the rear showing the opposite side and top of the motion-picture camera shown in Fig. 1.

We claim:

The ornamental design for a motion-picture camera, as shown.

OTTO WITTEL.
FREDERICK G. KNOWLES.
